CHEMOTHERAPEUTIC COMPOSITIONS CONTAINING N'-CYANO-PHENYL-TRIAZENECARBOXAMIDINES AND METHOD OF ADMINISTERING THE SAME

Adolph Whitten Vogel, Pearl River, N.Y., and Robert Allis Hardy, Jr., Ridgewood, and Charles Frederick Howell, Upper Saddle River, N.J., assignors to American Cyanamid Company, Stamford, Conn., a corporation of Maine

No Drawing. Filed June 11, 1964, Ser. No. 374,271
17 Claims. (Cl. 167—65)

This invention relates to compositions and methods of utilization thereof. More particularly, it relates to pharmaceutical compositions containing active anti-inflammatory agents and their use.

It is well known that many organic compounds belonging to the steroid field have anti-inflammatory activity. Among these prednisone, prednisolone, triamcinolone, etc., have been used for a number of years. However, there are usually inherent undesirable side effects particularly when used over a prolonged period of time.

We have now found that pharmaceutical compositions containing as active anti-inflammatory agents N'-cyanoaryl-triazene-carboxamidine derivatives are highly useful. The active components of the compositions may be illustrated by the following formula:

wherein R, R' and R'' are selected from the group consisting of hydrogen, halogen, lower alkoxy, lower alkylmercapto, lower alkyl and trifluoromethyl, R₂ is selected from the group consisting of hydrogen and lower alkyl and their pharmaceutically acceptable salts.

The triazene-carboxamidines of this invention are highly useful anti-inflammatory agents. They show excellent anti-inflammatory action at very low doses and possess distinct advantages over other non-steroid anti-inflammatory drugs such as the salicylates and phenylbutazone. The spread between the effective dose and the lethal dose is advantageously very large, with ratios of lethal to effective doses of about 100 to 1000 for representative compounds of this invention. The valuable anti-inflammatory properties of the compounds of this invention are readily demonstrated since they markedly reduce the size of a subcutaneous carrageenin-induced inflammatory granuloma. The active compounds of this invention may be used as the free substance or as non-toxic salts. They are generally administered orally or locally, and when so administered may be considered anti-inflammatory agents for the therapeutic treatment of rheumatoid disorders and other inflammatory conditions at individual doses ranging from about 5 to about 300 milligrams. The dosage regimen can be adjusted to provide optimum therapeutic response. Thus, for example, several doses may be administered daily, or the dose may be reduced proportionately as indicated by the exigencies of the therapeutic situation. It is also possible to adjust the dosage regimen so that individual doses are given intermittently at intervals of from several days to about a week or more with maintenance of an effective level of anti-inflammatory action. The active compositions of this invention may also be considered therapeutically useful by parenteral administration such as local injection into the inflamed area. For example, they may be administered by intra-articular injection into an inflamed joint. Other examples of parenteral routes for the therapeutic administration of the compounds of this

2

invention include intramuscular and intravenous administration of solutions and/or suspensions.

Due to the mobility of the hydrogen atoms, it is likely that these compounds may also exist in a variety of additional tautomeric forms which may change under the influence of different solvents, degree of acidity, and conditions for crystallization. For example, the preferred tautomeric form for the sodium salt of 1-aryl-N'-cyano-3-triazene-carboxamidines in methanol is shown:

It is to be understood that the present invention includes within its scope the above compounds as active therapeutic compositions in all such tautomeric forms.

The active compounds of this invention may exist in several forms. For example, as the free acids they are generally white, crystalline solids which are insoluble in water and sparingly soluble in organic solvents. The free acids are unstable when heated, when irradiated with ultra-violet light and when treated with mineral acids. They form salts with alkali and alkaline earth metal bases such as hydroxides and alkoxides. These metal salts are generally yellow, crystalline solids which are more stable to heat than the free acids and are somewhat more soluble in water. The free acids also form salts with strong organic bases such as choline and the like.

The compositions of the present invention are preferably presented for administration in unit dosage form as tablets, pills, capsules, powders, granules, sterile parenteral solutions or suspensions, oral solutions or suspensions and the like. For preparing solid compositions such as tablets, the principal active ingredient is mixed with conventional tabletting ingredients such as corn starch, lactose, sucrose, sorbitol, talc, stearic acid, magnesium stearate, dicalcium phosphate, gums and functionally similar materials as pharmaceutical diluents or carriers. The tablets or pills of the novel compositions can be laminated or otherwise compounded to provide a dosage form affording the advantage of prolonged or delayed action or predetermined successive action of the enclosed medication. For example, the tablet or pill can comprise an inner dosage and an outer dosage component, the latter being in the form of an envelope over the former. The two components can be separated by an enteric layer which serves to resist disintegration in the stomach and permits the inner component to pass intact into the duodenum or to be delayed in release. A variety of materials can be used for such enteric layers or coatings, such materials including a number of polymeric acids or mixtures of polymeric acids with such materials as shellac, shellac and cetyl alcohol, cellulose acetate, and the like. A particularly advantageous enteric coating comprises a styrene maleic acid copolymer together with known materials contributing to the enteric properties of the coating.

The liquid forms in which the novel composition of the present invention may be incorporated for administration include aqueous solutions and suspensions, suitable flavored syrups, oil suspensions, flavored emulsions with edible oils such as cottonseed oil, sesame oil, coconut oil, peanut oil and the like, as well as elixirs and similar pharmaceutical vehicles. Suitable dispersing or suspending agents for aqueous suspensions include synthetic and natural gums such as tragacanth, acacia, alginate, dextran, sodium carboxymethylcellulose, methylcellulose, polyvinylpyrrolidone, gelatin and the like. Sterile suspensions or solutions are required for parenteral use. Isotonic

preparations containing suitable preservatives are also highly desirable for injection use.

The term unit dosage form as used in the specification and claims refers to physically discrete units suitable as unitary dosages for animal subjects, each unit containing a predetermined quantity of active material calculated to produce the desired therapeutic effect in association with the required pharmaceutical diluent, carrier or vehicle. The specifications for the novel unit dosage forms of this invention are dictated by and are directly dependent on (a) the unique characteristics of the active material and the particular therapeutic effect to be achieved, and (b) the limitations inherent in the art of compounding such an active material for therapeutic use in animals as disclosed in detail in this specification, these being features of the present invention. Examples of suitable oral unit dosage forms in accord with this invention are tablets, capsules, pills, powder packets, granules, wafers, cachets, capsules, dropperfuls, amples, vials, segregated multiples of any of the foregoing, and other forms as herein described.

The active triazene-carboxamidines of this invention are readily prepared by the method illustrated by the following:

where R, R' and R'' are as previously described and X is halogen and M[⊕] is an alkali or alkaline earth metal.

By this method a suitable aniline derivative is diazotized and coupled with dicyandiamide in alkaline solution. The resulting N'-cyano-1-aryl-3-triazenecarboxamidines may be isolated as the metal salts by salting out or by conversion to the relatively insoluble free acid form.

The following examples describe anti-inflammatory testing, methods of preparing representative compounds of the invention, and pharmaceutical preparations containing representative anti-inflammatory agents.

EXAMPLE 1

Anti-inflammatory screening

Groups of two rats each are injected subcutaneously at the midline of the shaved sacral region with 0.5 ml. of a 2% aqueous carrageenin solution. (Carrageenin is a polygalactose sulfate extracted from Irish moss, a type of sea-weed. Subcutaneous injection of carrageenin causes rapid formation of an intense subcutaneous inflammatory reaction which subsequently develops into a connective tissue granuloma.) The compounds of this invention are suspended in aqueous 1% starch-sodium phosphate buffer solution; pH 6.5, and administered by oral tubing in 0.5 ml.; the total dose for each animal is 250 mg./kg. of body weight. One-half of each total dose is administered immediately following the carrageenin injection, and the second half of each total dose 4 hours later. Alternately, the total dose for each animal may be injected all at once immediately following the carrageenin injection. The animals are killed 24 hours after the carrageenin injections. The inflammatory reaction to the carrageenin results in the formation of exudate and gelatinous material which is removed and weighed. Control animals receive the carrageenin injection and the starch-sodium phosphate buffer solution orally without the test agent. Critical ratios (C/T—the ratio of weight of exudate and gelatinous material from control animals to weight of same

from test animals) are calculated, and compared by a 3-stage sequential screening procedure:

	Stage	Reject (C/T ratio)	Accept (C/T ratio)
1	$(C/T)_1$	1.11 or below	1.65 or above.
2	$(C/T)_1 \times (C/T)_2$	1.49 or below	2.23 or above.
3	$(C/T)_1 \times (C/T)_2 \times (C/T)_3$	Below 2.46	2.46 or above.

The above ratios represent a statistically designed method for detecting anti-inflammatory activity which is significantly different than the variability of control animals at the 95% confidence level. Thus, a compound which on the first stage give a $(C/T)_1 = 1.11$ or below is rejected; if the ratio is between 1.11 and 1.65 the compound is retested; and if the ratio is 1.65 or above the compound is accepted as active. On the second stage (re-test because $(C/T)_1$ is between 1.11 and 1.65), if the product $(C/T)_1 \times (C/T)_2$ is 1.49 or below the compound is rejected; if this product is between 1.49 and 2.23 the compound is given a third trial; if 2.23 or above the compound is accepted. On the third stage if the product $(C/T)_1 \times (C/T)_2 \times (C/T)_3$ is less than 2.46 the compound is rejected as inactive; but if this product is 2.46 or above the compound is accepted as an active anti-inflammatory agent.

When the compounds of this invention are tested by the above procedure, the following results are obtained.

Compound:	Product of C/T ratios (stage accepted)
N' - cyano - 1 - phenyl - 3 - triazene-carboxamidine sodium salt	1.88 (1); 2.17 (1)
N' - cyano - 1 - (p - chlorophenyl) - 3 - triazene-carboxamidine sodium salt	3.02 (1); 3.86 (1)
N' - cyano - 1 - (p - chlorophenyl) - 3 - triazene-carboxamidine	3.75 (1); 2.75 (1)
N' - cyano - 3 - (p - chlorophenyl) - 3 - methyl - 1 - triazene-carboxamidine sodium salt	2.74 (2); 3.75 (2)
N' - cyano - 1 - (5 - chloro-2-methoxyphenyl) - 3 - triazene-carboxamidine sodium salt	3.04 (1); 2.67 (1)
N' - cyano - 1 - (5 - chloro-2 - methylphenyl) - 3 - triazene-carboxamidine sodium salt	2.21 (1); 1.83 (1)
N' - cyano - 1 - (m - chlorophenyl) - 3 - triazene-carboxamidine sodium salt	3.15 (1); 2.90 (1)
N' - cyano - 1 - (p - methoxyphenyl) - 3 - triazene-carboxamidine sodium salt	3.54 (1); 3.22 (1)
N' - cyano - 1 - (p - methoxyphenyl) - 3 - triazene-carboxamidine magnesium salt	2.94 (1); 1.77 (1)
N' - cyano - 1 - (m - trifluoromethylphenyl) - 3 - triazene-carboxamidine sodium salt	1.97 (1); 2.64 (1)
N' - cyano - 1 - (m - methoxyphenyl) - 3 - triazene-carboxamidine potassium salt	2.87 (1); 2.63 (1)
N' - cyano - 1 - (p - tolyl) - 3 - triazene-carboxamidine sodium salt	3.08 (2); 1.65 (1)
N' - cyano - 1 - (p - ethoxyphenyl) - 3 - triazene-carboxamidine sodium salt	2.51 (1); 4.14 (1)
N' - cyano - 1 - (o - methoxyphenyl) - 3 - triazene-carboxamidine sodium salt	2.70 (1); 6.08 (3)

N' - cyano - 1 - (p - methoxyphenyl) - 3 - triazene carboxamidine choline salt	1.96 (1); 4.28 (1)
N' - cyano - 1 - (3,4 - dimethoxyphenyl) - 3 - triazene carboxamidine sodium salt	2.67 (1); 3.50 (2)
N' - cyano - 1 - (o - trifluoromethylphenyl) - 3 - triazene carboxamidine sodium salt	3.13 (2); 1.86 (1)
N' - cyano - 1 - (o - tolyl) - 3 - triazene carboxamidine sodium salt	1.70 (1); 2.09 (1)

and Wilcoxon. The LD_{50} is the median lethal dose which causes 50% mortality.

The effective doses (ED_{29} and ED_{50}) and median lethal doses (LD_{50}) are compared for a given test agent to demonstrate that the anti-inflammatory activity is obtained at non-toxic dose levels with a desirably wide spread between the effective and toxic dose levels. An anti-inflammatory index (ratio of the lethal to the ED_{29} dose levels) may be calculated.

When representative active compounds of the present invention are evaluated by the above described procedures the following results are obtained:

Compound	ED_{29} , mg./kg., p.o.	ED_{50} , mg./kg., p.o.	LD_{50} , mg./kg., p.o.	Anti-inflammatory Index (LD_{50}/ED_{29})
N'-cyano-1-(5-chloro-2-methyl phenyl)-3-triazene carboxamidine sodium salt	15	63	>900	>60
N'-cyano-1-phenyl-3-triazene carboxamidine sodium salt	24	73	700	29
N'-cyano-1-(p-methoxyphenyl)-3-triazene carboxamidine sodium salt	0.7	5	1,030	1,390
N'-cyano-1-(p-chlorophenyl)-3-triazene carboxamidine sodium salt	10	33	1,250	125
N'-cyano-1-(o-tolyl)-3-triazene carboxamidine sodium salt	33	120	>1,000	>30
N'-cyano-1-(m-methoxyphenyl)-3-triazene carboxamidine potassium salt	12.5	54		
N'-cyano-1-(o-methoxyphenyl)-3-triazene carboxamidine sodium salt	26	110		
N'-cyano-1-(p-ethoxyphenyl)-3-triazene carboxamidine sodium salt	2.8	17		
N'-cyano-1-(m-chlorophenyl)-3-triazene carboxamidine sodium salt	10	35		
N'-cyano-1-(5-chloro-2-methoxyphenyl)-3-triazene carboxamidine sodium salt	17	80		
N'-cyano-1-(m-trifluoromethylphenyl)-3-triazene carboxamidine sodium salt	35	74		
N'-cyano-1-(p-tolyl)-3-triazene carboxamidine sodium salt	22	82		
Phenylbutazone	12.7	>250	445	3.5
Triamcinolone	3.5	65	>500	>140

N' - cyano - 1 - (p - methylmercaptophenyl) - 3 - triazene carboxamidine sodium salt	2.72 (1); 2.26 (1)	35
N' - cyano - 1 - (p - ethylphenyl) - 3 - triazene carboxamidine sodium salt	4.68 (2)	40
N' - cyano - 1 - (3,4,5 - trimethoxyphenyl) - 3 - triazene carboxamidine sodium salt	4.68 (2)	45

EXAMPLE 2

Anti-inflammatory evaluation

The general procedure of Example 1 is repeated. The carrageenin granuloma is produced in the same manner and the method of administration of the test agents is identical. However, about 5 graded doses of the test agent (accepted as active in the screening procedure and confirmed by replication of the screening procedure) are administered to 4 rats at each dose level. Mean abscess weights of the control and treated groups are recorded. The entire experiment is replicated three times, the results are subjected to statistical analysis, and a dose-response curve is calculated. This data is used to calculate effective dose levels for relative potency comparisons. For example, the ED_{29} is defined as the dose of a test agent which produces a 29% reduction of mean abscess weights compared to the control groups. The 29% reduction of inflammatory response represents the midpoint of the dose-response curve for the anti-inflammatory drug, phenylbutazone, and is used for relative potency comparisons with this drug. An ED_{50} is defined as the dose of a test agent which produces a 50% reduction in the subcutaneous inflammatory response to carrageenin as measured by the mean abscess weights. The ED_{50} may also be used for relative potency comparisons.

Toxicity: Groups of ten rats each are administered graded doses of the test agent by oral tubing and observed daily for 7 to 14 days. The cumulative number of deaths in each group at each dose level is recorded and this data is used to calculate an LD_{50} by the method of Litchfield

EXAMPLE 3

Anti-inflammatory activity by local administration

The general procedure of Example 2 is repeated. The

Compound	ED_{29} , mg./kg., s.c.	ED_{50} , mg./kg., s.c.
N'-cyano-1-(5-chloro-2-methoxyphenyl)-3-triazene carboxamidine sodium salt	1.2	4.3
N'-cyano-1-(p-methoxyphenyl)-3-triazene carboxamidine sodium salt	0.4	0.9
N'-cyano-1-(p-chlorophenyl)-3-triazene carboxamidine magnesium salt	0.9	1.6
N'-cyano-1-(m-methoxyphenyl)-3-triazene carboxamidine potassium salt	0.8	1.9
N'-cyano-1-(o-methoxyphenyl)-3-triazene carboxamidine sodium salt	0.4	1.6
N'-cyano-1-(p-ethoxyphenyl)-3-triazene carboxamidine sodium salt	1.2	2.2
N'-cyano-1-phenyl-3-triazene carboxamidine sodium salt	1.2	2.0
N'-cyano-1-(p-chlorophenyl)-3-triazene carboxamidine sodium salt	0.7	2.4
N'-cyano-1-(p-tolyl)-3-triazene carboxamidine sodium salt	1.9	3.6
Phenylbutazone	30	>1,000
Triamcinolone	2.5	30

carrageenin granuloma is produced in the same manner, but the test agents are administered subcutaneously into the same site as the carrageenin injection immediately following the carrageenin injection.

Graded doses are administered to 4 rats at each dose level and the 24 hour mean abscess weights of the control and treated groups are recorded. The results are subjected to statistical analysis, a dose-response curve is calculated and effective dose levels are determined.

When representative active compounds of the present invention are evaluated by the above-described procedure, the following results are obtained:

EXAMPLE 4

Preparation of N'-cyano-1-(p-methoxyphenyl)-3-triazene carboxamidine

A solution of 12.3 grams of p-anisidine in 22 milliliters of concentrated hydrochloric acid and 120 milliliters of

water is warmed and then cooled quickly in an ice or ice-acetone bath to -5° to -15° C. The mixture is treated in the cold with a solution of 7.2 grams of sodium nitrite in 25 milliliters of water. The resulting solution yields a blue-violet color with potassium iodide starch paper indicative of a slight excess of nitrous acid. The solution is treated with charcoal powder and filtered into a solution of 120 milliliters of 10% sodium hydroxide, 10.1 grams of dicyandiamide and 400 milliliters of water. The resulting solution (pH 8-10) is warmed at 30° to 50° C. for $\frac{1}{2}$ to 2 hours until a test sample placed on filter paper no longer gives a red test for diazonium salt with alkaline "R-salt" (2-amino-8-naphthol 3,6-disulfonic acid). The solution is cooled, treated with charcoal and filtered directly into an ice-cold solution of 182 milliliters of 2 N acetic acid and 700 milliliters of water. The free acid is collected by filtration and pressed dry. It may be purified by dissolving it in a solution of 4.6 grams of lithium hydroxide in 200 milliliters of water charcoaling and filtering into 250 milliliters of 2 N acetic acid. The purified acid is collected by filtration, pressed as dry as possible and mixed with a solution of 10.8 grams of sodium methoxide in 75 milliliters of ethanol. Cooling yields the yellow sodium salt which melts at about 233° - 234° C. with decomposition. This salt is purified by recrystallization from dimethylformamide-ether or from methanol followed by boiling briefly with acetone or acetonitrile to remove traces of solvent.

The magnesium salt is prepared from the sodium salt by treating 2.0 grams of the latter dissolved in 8 milliliters of water with 8.3 milliliters of 2 N acetic acid diluted with 48 milliliters of ice water. The colorless acid precipitates, is collected on a filter and dried thoroughly over phosphorus pentoxide under reduced pressure at room temperature. The acid is suspended in 30 milliliters of absolute methanol under nitrogen, treated with 8 milliliters of 1 N magnesium methoxide in methanol and stirred until the colorless acid has dissolved and the yellow orange salt has separated. The salt is collected by filtration under nitrogen and dried at once over phosphorus pentoxide. The magnesium salt decomposes slowly with no definite melting point between about 90° and 160° C. and rapidly absorbs moisture from the atmosphere.

The choline salt is prepared from the acid by treating a sample with slightly less than 1 equivalent of aqueous 1 M β -hydroxyethyltrimethylammonium hydroxide. The mixture is filtered and the filtrate lyophilized. The residue is recrystallized twice from isopropanol to give yellow platelets of the choline salt which melts at 114° - 116° C.

EXAMPLE 5

Preparation of 3-(p-chlorophenyl)-N'-cyano-3-methyl-1-triazene carboxamidine

A solution of 7.3 grams of 1-(p-chlorophenyl)-N'-cyano-3-triazene carboxamidine in 100 ml. of 1 M lithium hydroxide at about 25° C. is treated with 4.7 milliliters of dimethyl sulfate. After being stirred for 30 minutes this mixture is diluted with 50 milliliters of 1 M lithium hydroxide and filtered. The product is washed thoroughly with water and dried over phosphorus pentoxide under reduced pressure at room temperature. The resulting mixture of isomers is dissolved in 1500 milliliters of methylene chloride and adsorbed into a chromatographic column of 150 grams of 100-200 mesh silica gel and eluted with mixtures of methylene chloride and ether until a yellow color due to the desired component appears in the eluate. 3-(p-chlorophenyl)-N'-cyano-3-methyl-1-triazene carboxamidine is eluted with ether or with a 4:1 (v/v) methylene chloride-ether mixture until the eluate is no longer yellow. The eluate is concentrated and the product is recrystallized from methanol to give yellow prisms which melt at 181° - 182° C. and are characterized by

$\lambda_{\text{max.}}^{\text{CH}_3\text{OH}}$ 331-336 m μ ($\epsilon=18,700$)

in the ultraviolet spectrum.

EXAMPLE 6

Preparation of N'-cyano-1-phenyl-3-triazene carboxamidine

The general procedure of Example 4 is repeated. From the diazotization of aniline and coupling with dicyandiamide, this product is obtained as a sodium salt, melting point 242° - 244° C. with decomposition and ultraviolet absorption at

$\lambda_{\text{max.}}^{0.1\text{NaOH}}$ 330 m μ

15 when purified by the procedures previously described.

EXAMPLE 7

Preparation of N'-cyano-1-(p-chlorophenyl)-3-triazene carboxamidine

20 Using the procedure of Example 4 and diazotizing p-chloroaniline and coupling with dicyandiamide, the above product is obtained as a sodium salt, melting point 247° - 248° C. with decomposition and ultraviolet absorption at

$\lambda_{\text{max.}}^{0.1\text{NaOH}}$ 332 m μ

when purified by the procedures previously described. The free acid is obtained by treating an ice cold solution of 0.5 gram of the sodium salt in 25 milliliters of water 30 with 2 milliliters of 2 N acetic acid. The precipitate is collected and dried in the dark over phosphorus pentoxide under reduced pressure at room temperature. The free acid melts at about 149° - 151° C. with decomposition and evolution of gas and shows ultraviolet absorption at

$\lambda_{\text{max.}}^{\text{CH}_3\text{OH}}$ 307 m μ

EXAMPLE 8

Preparation of N'-cyano-1-(5-chloro-2-methoxyphenyl)-3-triazene carboxamidine

40 When the procedure of Example 4 is repeated with the diazotization of 5-chloro-2-methoxyaniline and coupling with dicyandiamide, the above product is obtained as a sodium salt, melting point 272° - 274° C. with decomposition and ultraviolet absorption at

$\lambda_{\text{max.}}^{0.1\text{NaOH}}$ 338 m μ

50 when purified by the procedures previously described.

EXAMPLE 9

Preparation of N'-cyano-1-(5-chloro-2-methylphenyl)-3-triazene carboxamidine

55 Using the procedure of Example 4 with the diazotization of 5-chloro-2-methylaniline and coupling with dicyandiamide, this product is obtained as a sodium salt, melting point 234° - 237° C. with decomposition and ultraviolet absorption at

$\lambda_{\text{max.}}^{0.1\text{NaOH}}$ 231 m μ

when purified by the procedures previously described.

EXAMPLE 10

Preparation of N'-cyano-1-(m-chlorophenyl)-3-triazene carboxamidine

65 When the procedure of Example 4 is used with the diazotization of m-chloroaniline and coupling with dicyandiamide, this product is obtained as a sodium salt, melting point 234° - 236° C. with decomposition and ultraviolet absorption at

$\lambda_{\text{max.}}^{0.1\text{NaOH}}$ 337 m μ

75 when purified by the procedure previously described.

EXAMPLE 11

Preparation of N'-cyano-1-(m-trifluoromethylphenyl)-3-triazene carboxamidine

Using the procedure of Example 4 with the diazotization of m-trifluoromethylaniline and coupling with dicyandiamide, the above product is obtained as a sodium salt, melting point 227° C. with decomposition and ultra violet absorption at

 $\lambda_{\max}^{0.1 \text{ NaOH}} 332 \text{ m}\mu$

when purified by the procedures previously described.

EXAMPLE 12

Preparation of N'-cyano-1-(m-methoxyphenyl)-3-triazene carboxamidine

The general procedure of Example 4 is repeated. From the diazotization of m-anisidine and coupling with dicyandiamide, this product is obtained as a potassium salt, melting point 229°-230° C. with decomposition and ultraviolet absorption at

 $\lambda_{\max}^{0.1 \text{ NaOH}} 333 \text{ m}\mu$

when purified by the procedures previously described.

EXAMPLE 13

Preparation of N'-cyano-1-(p-tolyl)-3-triazene carboxamidine

When the procedure of Example 4 is used with the diazotization of p-toluidine and coupling with dicyandiamide, this product is obtained as a sodium salt, melting point 245° C. with decomposition and ultraviolet absorption at

 $\lambda_{\max}^{0.1 \text{ NaOH}} 334 \text{ m}\mu$

when purified by the procedures previously described.

EXAMPLE 14

Preparation of N'-cyano-1-(p-ethoxyphenyl)-3-triazene carboxamidine

The procedure of Example 4 is repeated. From the diazotization of p-ethoxyaniline and coupling with dicyandiamide, this product is obtained as a sodium salt, melting point 243°-245° C. with decomposition and ultraviolet absorption at

 $\lambda_{\max}^{0.1 \text{ NaOH}} 340 \text{ m}\mu$

when purified by the procedures previously described.

EXAMPLE 15

Preparation of N'-cyano-1-(o-methoxyphenyl)-3-triazene carboxamidine

Using the procedure of Example 4 with the diazotization of o-anisidine and coupling with dicyandiamide, the above product is obtained as a sodium salt, melting point 230°-231° C. with decomposition and ultraviolet absorption at

 $\lambda_{\max}^{0.1 \text{ NaOH}} 340 \text{ m}\mu$

when purified by the procedures previously described.

EXAMPLE 16

Preparation of N'-cyano-1-(3,4-dimethoxyphenyl)-3-triazene carboxamidine

When the procedure of Example 4 is used with the diazotization of 4-aminoveratrole and coupling with dicyandiamide, this product is obtained as a sodium salt, melting point 164°-166° C. with decomposition and ultraviolet absorption at

 $\lambda_{\max}^{0.1 \text{ NaOH}} 348 \text{ m}\mu$

when purified by the procedures previously described.

EXAMPLE 17

Preparation of N'-cyano-1-(o-trifluoromethylphenyl)-3-triazene carboxamidine

When the procedure of Example 4 is used with the diazotization of o-aminobenzotrifluoride and coupling with dicyandiamide, this product is obtained as a sodium salt, melting point 211°-213° C. with decomposition and ultraviolet absorption at

 $\lambda_{\max}^{0.1 \text{ NaOH}} 330 \text{ m}\mu$

when purified by the procedures previously described.

EXAMPLE 18

Preparation of N'-cyano-1-(o-tolyl)-3-triazene carboxamidine

When the procedure of Example 4 is used with the diazotization of o-toluidine and coupling with dicyandiamide, this product is obtained as a sodium salt, melting point 185°-195° C. with decomposition and ultraviolet absorption at

 $\lambda_{\max}^{0.1 \text{ NaOH}} 334 \text{ m}\mu$

when purified by the procedures previously described.

25

EXAMPLE 19

Preparation of N'-cyano-1-(p-methylmercaptophenyl)-3-triazene carboxamidine

When the procedure of Example 4 is used with the diazotization of p-methylmercaptoaniline and coupling with dicyandiamide, this product is obtained as a sodium salt, melting point 258°-259° C. with decomposition and ultraviolet absorption at

 $\lambda_{\max}^{0.1 \text{ NaOH}} 356 \text{ m}\mu$

when purified by the procedures previously described.

25

EXAMPLE 20

Preparation of N'-cyano-1-(p-ethylphenyl)-3-triazene carboxamidine

When the procedure of Example 4 is used with the diazotization of p-ethylaniline and coupling with dicyandiamide, this product is obtained as a sodium salt, melting point 139°-141° C. with decomposition and ultraviolet absorption at

 $\lambda_{\max}^{0.1 \text{ NaOH}} 335 \text{ m}\mu$

when purified by the procedures previously described.

50

EXAMPLE 21

Preparation of N'-cyano-1-(3,4,5-trimethoxyphenyl)-3-triazene carboxamidine

When the procedure of Example 4 is used with the diazotization of 3,4,5-trimethoxyaniline and coupling with dicyandiamide, this product is obtained as a sodium salt, melting point 157°-159° C. with decomposition and ultraviolet absorption at

 $\lambda_{\max}^{0.1 \text{ NaOH}} 340 \text{ m}\mu$

when purified by the procedures previously described.

60

EXAMPLE 22

Capsules containing N'-cyano-1-(p-methoxyphenyl)-3-triazene carboxamidine

	Per Capsule (g.)	For 10,000 Capsules (g.)
70 Active ingredient: N'-cyano-1-(p-methoxyphenyl)-3-triazene carboxamidine sodium salt	0.025	250
Lactose	0.074	740
Magnesium stearate (1%)	0.001	10
	0.100	1,000

75

The dry ingredients are thoroughly mixed and 0.100 g. of the mix is placed in each gelatin capsule.

We claim:

1. A chemotherapeutic composition for use in animals as an anti-inflammatory agent which comprises a pharmaceutical carrier and a compound selected from the group consisting of N'-cyano-aryl-triazene-carboxamidines of the formula:

10

wherein R, R' and R'' are selected from the group consisting of hydrogen, halogen, lower alkoxy, lower alkylmercapto, lower alkyl and trifluoromethyl, R₂ is selected from the group consisting of hydrogen and lower alkyl and non-toxic pharmaceutically acceptable salts thereof.

2. A chemotherapeutic, anti-inflammatory composition useful in animals which comprises a pharmaceutical carrier and from about 5 to about 300 milligrams of a compound selected from the group consisting of N'-cyano-aryl-triazene-carboxamidines of the formula:

wherein R, R' and R'' are selected from the group consisting of hydrogen, halogen, lower alkoxy, lower alkylmercapto, lower alkyl and trifluoromethyl, R₂ is selected from the group consisting of hydrogen and lower alkyl and non-toxic pharmaceutically acceptable salts thereof.

3. A chemotherapeutic composition in accordance with claim 2 wherein the active component is N'-cyano-1-(5-chloro-2-methylphenyl)-3-triazene-carboxamidine.

4. A chemotherapeutic composition in accordance with claim 2 wherein the active component is N'-cyano-1-(p-methoxyphenyl)-3-triazene-carboxamidine.

5. A chemotherapeutic composition in accordance with claim 2 wherein the active component is N'-cyano-1-phenyl-3-triazene-carboxamidine.

6. A chemotherapeutic composition in accordance with claim 2 wherein the active component is N'-cyano-1-(p-chlorophenyl)-3-triazene-carboxamidine.

7. A chemotherapeutic composition in accordance with claim 2 wherein the active component is N'-cyano-3-(p-chlorophenyl)-3-methyl-1-triazene-carboxamidine.

8. A chemotherapeutic, anti-inflammatory composition useful in animals which comprises a pharmaceutical carrier and from about 5 to about 300 milligrams of N'-

cyano - 1 - (m - trifluoromethylphenyl) - 3 - triazene-carboxamidine sodium salt.

9. A method for treatment of inflammatory and rheumatic condition in animals by administering a composition comprising a pharmaceutical carrier and from about 5 to about 300 milligrams of a compound selected from the group consisting of N'-cyano-aryl-triazene-carboxamidines of the formula:

10

wherein R, R' and R'' are selected from the group consisting of hydrogen, halogen, lower alkoxy, lower alkylmercapto, lower alkyl and trifluoromethyl, R₂ is selected from the group consisting of hydrogen and lower alkyl and non-toxic pharmaceutically acceptable salts thereof.

20 10. A method for treatment of inflammatory and rheumatic conditions in accordance with claim 9 in which the compound is N'-cyano-1-(5-chloro-2-methylphenyl)-3-triazene-carboxamidine.

25 11. A method in accordance with claim 9 in which the N'-cyano-aryl-triazene-carboxamidine is N'-cyano-1-(p-methoxyphenyl)-3-triazene-carboxamidine.

12. A method in accordance with claim 9 in which the N'-cyano-aryl-triazene-carboxamidine is N'-cyano-1-phenyl-3-triazene-carboxamidine.

30 13. A method in accordance with claim 9 in which the N'-cyano-aryl-triazene-carboxamidine is N'-cyano-1-(p-chlorophenyl)-3-triazene-carboxamidine.

14. A method in accordance with claim 9 in which the N'-cyano-aryl-triazene-carboxamidine is N'-cyano-3-(p-chlorophenyl)-3-methyl-1-triazene-carboxamidine sodium salt.

35 15. A method in accordance with claim 9 in which the N'-cyano-aryl-triazene-carboxamidine is N'-cyano-1-(m-trifluoromethylphenyl)-3-triazene-carboxamidine sodium salt.

40 16. A method in accordance with claim 9 in which the N'-cyano-aryl-triazene-carboxamidine is N'-cyano-1-(p-ethoxyphenyl)-3-triazene-carboxamidine sodium salt.

45 17. A method in accordance with claim 9 in which the N'-cyano-aryl-triazene-carboxamidine is N'-cyano-1-(m-methoxyphenyl)-3-triazene-carboxamidine potassium salt.
